(57) CLAIM

We claim, the ornamental design for a display screen or portion thereof with animated graphical user interface, as shown and described.

DESCRIPTION

FIG. 1 is a front view of the first image in a sequence for a display screen or portion thereof with animated graphical user interface, showing our new design;

FIG. 2 is a front view of the second image thereof;

FIG. 3 is a front view of the third image thereof;

FIG. 4 is a front view of the fourth image thereof;

FIG. 5 is a front view of the fifth image thereof;

FIG. 6 is a front view of the sixth image thereof;

FIG. 7 is a front view of the seventh image thereof;

FIG. 8 is a front view of the eighth image thereof;

FIG. 9 is a front view of the ninth image thereof;

FIG. 10 is a front view of the tenth image thereof;

FIG. 11 is a front view of the eleventh image thereof;

FIG. 12 is a front view of the twelfth image thereof;

FIG. 13 is a front view of the thirteenth image thereof;

FIG. 14 is a front view of the fourteenth image thereof; and,

FIG. 15 is a front view of the fifteenth image thereof.

The appearance of the animated graphical user interface sequentially transitions between the images shown in FIGS. 1-15. The process or period in which one image transitions to another forms no part of the claimed design. The dual set of outermost broken lines illustrate the display screen or portion thereof. The broken line showing of alphanumeric characters and the dot-dash circular line illustrate portions of the animated graphical user interface. None of the broken lines form part of the claimed design.
